CLOTHES HANGER

Sydney H. Gleich, Brooklyn, N. Y., and Marc S. Landau, Dover, Del., assignors to International Latex Corporation, Dover, Del., a corporation of Delaware

Application October 31, 1956, Serial No. 43,605

Term of patent 14 years

(Cl. D80—8)

Fig. 1 is a front elevational view of a clothes hanger embodying our design; and

Fig. 2 is a sectional view taken on the line 2—2 of Fig. 1.

The opposite side is substantially like the side shown, except that it is repoussé in form.

We claim:

The ornamental design for a clothes hanger, as shown and described.
